THEATRICAL AND ADVERTISING DISPLAY

Frederic Shipman, New York, N. Y.

Application June 25, 1945, Serial No. 601,464

7 Claims. (Cl. 272—13)

1

My invention is concerned with theatrical and advertising displays in which the kaleidoscopic effects of mirrors are involved.

The main purpose of the invention is to produce such effects by sudden changes in the appearance of the displayed objects, which are brought about by a displacement of parts of the complete assembly and by the removal of other parts and substitution of replacements in their stead. Thus, for example, the stage or the display arena may comprise a multitude of women who, as if by magic, are suddenly turned into men; or the stage may be filled with young girls who suddenly are turned into old hags, and vice versa; or the stage may be occupied by a mass of people characterized by their unique costume denoting some definite nationality and, suddenly, they are changed into people of a different nationality. One of the purposes of the invention is to interrupt a V-shaped set of mirrors by incorporating in the walls of the V a turn table on which a double mirror is set up, one or the other of these mirrors becoming an integral part of the V, and a different illusion being presented according to which one of these mirrors is aligned with the reflecting surface of the members of the V. It is also a purpose of the invention to provide the V with a movable apex, affording not only a good entry onto the triangular stage formed by the V, but an influx of various individuals or objects while removing those on the stage at the time. These and other objects of the invention will become better understood from the specification which follows and from the accompanying drawing, in which

Figure 1 is a horizontal cross section of a device embodying the invention, taken along the line 1—1 of Figure 2.

Figure 2 is a front elevational view of the device some portions of which are in cross section.

Referring to the figures in detail, 1 and 2 are two plane sheets set up vertically, in the form of a V, on the triangular stage defined between them. The inner layers of the sheets 1 and 2 have reflecting surfaces 3, which may be mirrors, while the outer layers 4 are of any suitable material for backing the reflecting surfaces, such as wood or panelling. The sheets 1 and 2 form an apex 9, the reference being not merely to the point of contact but to the entire portion separable from the rest of the V. The sheets 1 and 2 are interrupted intermediate their ends. In the interrupted spaces turn tables 5 and 6 are set up in wells 19 extending below the flooring 18 of the stage, the floor of the turn table

2

being level with the flooring 18 of the stage. On the tables 5 and 6 are erected vertically and back to back double mirrors 7 and 8, which need not necessarily be mirrors, but may be sheets provided with reflecting surfaces extending at least as high as the V. The mirrors 7 and 8 are held together at the top by U-shaped clamps 15 arranged immediately underneath the ceiling, these clamps 15 being provided with pivots 16 on which the mirrors 7 and 8, together with the tables 5 and 6, may turn. The tables 5 and 6 are provided with casters 14 which run on circular tracks 17. The tracks 17, together with the pivots 16, define the rotary motion of the tables about vertical axes. The reflecting surface 7 and the other reflecting surface 8 (when the table is turned by 180 degrees) are flush with the corresponding one of the reflecting surfaces 3 of the sheets 1 and 2.

20 The apex of the V is movable parallel to the proscenium of the stage by means of wheels 11 running on tracks 10. The means for moving the apices, of which there is a continuous series, although only two of them are shown in the drawing, is omitted since it presents nothing that is not fully known in the art. The apices are all similar and are connected in the manner shown so that one apex can replace the other when moved along the tracks 10. The means 25 for moving the apices on the tracks 10 and the means for rotating the tables 5 and 6 may be manual or mechanical. Also, the means may be separate and distinct, or they may be joint and cooperative.

30 The open ends of the sheets 1 and 2 are concealed by angularly formed sheets 12 and 13, a portion of which extends into the proscenium of the stage. Entry of various objects onto the stage is afforded between the open ends of the sheets 1 and 2, and the masking sheets 12 and 13. Such objects are not reflected in the mirrors until they pass by the sheets 1 or 2 into the space covered by the portion of the sheet 12 or 13 extending into the proscenium.

45 The arrangement as here disclosed permits of very interesting cooperation between the turn tables and the movable apices. For example, if it is desired to create some effect depending on a definite color scheme to which the objects in one of the apices contribute, and objects on one side of a turn table contribute to the same color scheme, after which it is desired to create another effect depending on another color scheme, objects contributing to this other color scheme are placed in another one of the moving

apices, at the same time changing the objects on the turn table by arranging them on the opposite side of the turn table, and then moving both, the second apex and the table, so that the new effect is created by both in their new positions. As to the entries at 12 and 13, it should be noted that they constitute the only entries when a definite apex is moved into view and the turn tables are in one of their operative positions. For example, suppose that a chorus or part of an orchestra are brought into view by rotating the turn tables and moving one of the apices onto the stage, and it is desired to introduce additional subjects onto the stage, such as one or two soloists, the chorus, orchestra and soloists forming an ensemble, the soloists would enter at 12 or 13. In other words, the three elements of the total combination always work in unison with one another, the turn tables, the apices and the masked entries.

It is to be understood that when the word mirror is used anywhere in the specification or claims, the term is meant to describe any sheet having a reflecting surface.

I claim:

1. A theatrical or advertising display, including a pair of sheets arranged to form a V and defining a triangular stage between them, a reflecting surface on each one of said sheets on one side thereof, at least one of said sheets having an interruption intermediate its ends, a turn table within said interruption level with said stage, a tier diametrically disposed on said turn table at a right angle thereto, a reflecting surface on each side of said tier, said turn table being in operative position when one or the other of said tier reflecting surfaces is in alignment with the reflecting surface of the corresponding interrupted sheet, and means of entry onto said stage other than through said turn tables.

2. A pair of sheets arranged to form a V and defining a triangular stage between them, a reflecting surface on one side of each sheet, and means of entry onto said stage at the apex of said V, comprising a train of successive apices identical with the original apex of the V, said train being movable across said stage into positions wherein the reflecting surfaces of an apex are in alignment with the reflecting surfaces of said sheets.

3. A theatrical or advertising display according to claim 1, wherein the last mentioned means of entry onto the stage comprises a train of successive apices identical with the original apex of the V, said train being movable across the stage into positions wherein the reflecting surfaces of an apex are in alignment with the reflecting surfaces of the V forming sheets, and objects in successive apices may be coordinated with objects on opposite sides of a turn table.

4. A pair of sheets formed into a V and defining a triangular stage between them, and an angularly formed masking sheet at the open end of each V forming sheet, reflecting surfaces on

one side of each V forming sheet, said masking sheets extending partially into the proscenium of said stage and affording means of entry thereonto between the open ends of said V forming sheets and said masking sheets, such entry, however, being subject to reflections in said reflecting surfaces only after the entry making object has reached the extension of said angularly formed sheet into the proscenium.

5. A theatrical or advertising display according to claim 1, wherein an angularly formed masking sheet is erected at the open end of each V forming sheet, partly extending into the proscenium of the stage, and the means of entry onto the stage is between said open ends and said angularly formed masking sheet.

6. A theatrical or advertising display, including a pair of sheets arranged to form a V and defining a triangular stage between them, a reflecting surface on each one of said sheets having an interruption intermediate its ends, a turn table within said interruption level with said stage, a tier diametrically disposed on said turn table at a right angle thereto, a reflecting surface on each side of said tier, said turn table being in operative position when one or the other of said tier reflecting surfaces is in alignment with the reflecting surface of the corresponding interrupted V forming sheet, means of entry onto said stage through the apex of the V, said means comprising a train of successive apices identical with the original apex of the V movable across said stage into positions wherein the reflecting surfaces of an apex are in alignment with the reflecting surfaces of the V forming sheets, and an angularly formed sheet for masking the open ends of the V forming sheets partially extending into the proscenium of said stage and affording means of entry onto said stage between said open ends and said masking sheets, the last mentioned means of entry being subject to coordination with the entry through the apex of the V and through said turn tables.

7. A theatrical or advertising display, including a pair of sheets arranged to form a V and defining a triangular stage between them, a reflecting surface on at least one of said sheets having an interruption intermediate its ends, a turn table within said interruption level with said stage, a tier diametrically disposed on said turn table at a right angle thereto, a reflecting surface on each side of said tier, said turn table being in operative position when one or the other of said tier reflecting surfaces is in alignment with the reflecting surface of the corresponding interrupted V forming sheet, and an angularly formed sheet for masking the open ends of the V forming sheets partially extending into the proscenium of said stage and affording means of entry onto said stage between said open ends of said masking sheets, the latter means being subject to coordination with the entry through said turn table.

FREDERIC SHIPMAN.
